PREPARATION OF NORMAL-ALKYL RESERPATES AND ALKYL DESERPIDATES

William Irving Taylor, Summit, N. J., assignor to Ciba Pharmaceutical Products, Inc., Summit, N. J., a corporation of New Jersey

No Drawing. Application April 9, 1956
Serial No. 576,834

6 Claims. (Cl. 260—287)

This invention relates to a process for the production of organic compounds and the salts thereof. More particularly the invention concerns a process for the production of compounds of the formula:

wherein R represents hydrogen or lower alkyl, R' stands for lower alkyl and R'' for hydrogen or an acyl radical, and X represents the unsubstituted or substituted remainder of a benzene nucleus, and their salts.

Lower alkyl radicals are for example methyl or ethyl, an acyl radical is preferably that of an aliphatic, araliphatic, aromatic or heterocyclic acid, such as lower fatty acids, e. g. acetic or propionic acid, phenyl carboxylic acids, e. g. benzoic acid or preferably lower alkoxybenzoic acids such as 4-methoxy-benzoic acid, 3,4-dimethoxy-benzoic acid, 3,4,5-trimethoxy-benzoic acid, 3,4-methylenedioxy-benzoic acid, cinnamic acids, e. g. methoxy-cinnamic acid, dimethoxy-cinnamic acid or 3,4,5-trimethoxy-cinnamic acid, monocyclic heterocyclic carboxylic acids, e. g. furane-2-carboxylic acid, thiophene-2-carboxylic acid or nicotinic acid, or aryl sulfonic acids, e. g. toluene sulfonic acids.

It is known that the reduction of synthetically obtainable compounds of the formula:

wherein R, R' and R'' have the above-mentioned meaning and A stands for an anion such as halogen ion, e. g. the chloride ion or a nitrate ion, with sodium borohy-

2

dride does not lead to the desired compounds having the 3-epi-alloyohimbane configuration like reserpine, i. e.

15 but to the corresponding iso-compounds of the formula:

I have now found that the 3-unsaturated compounds of the formula:

30 wherein X, R, R', R'' and A have the aforesaid meanings can be reduced to yield the desired compounds having the 3-epi-alloyohimbane configuration, e. g.

45 This end can be achieved by liberating the free base of the quaternary starting material and reducing it with catalytically activated hydrogen under conditions which do not affect the double bonds in rings A and B.

50 Agents capable of liberating a base from a quaternary salt are alkaline agents, e. g. alkali or earth alkali metal hydroxides such as potassium or sodium hydroxide or ammonia such as aqueous ammonia. The hydrogen used

in the reduction step is activated by catalysts containing at least one element selected from the eighth group of the periodic system, e. g. platinum or palladium such as 10 percent palladium on charcoal. The reduction is carried out at room temperature or raised temperature, under normal or elevated pressure, preferably it is performed at an elevated temperature and under pressure.

The starting materials for the process of the invention are compounds of the formula:

wherein A, X, R, R', and R" having the aforesaid meaning, preferably compounds of the formula:

wherein R, R' and R" have the aforesaid meaning, R''' stands for hydrogen or methoxy and A represents an anion such as a halogen ion, e. g. a chloride ion, or a nitrate ion. Thus, it is, for example, possible to liberate 40 the free base of a compound of the formula:

by treatment with potassium hydroxide and reduce the compound thus obtained with hydrogen in the presence of 10 percent palladium on charcoal so as to form the compound of the formula:

The starting materials can be used in the form of their optically active antipodes or in the form of the racemates. Depending on the choice of the starting material, the saturated final compound is laevo or dextro-rotary or racemic. Racemic mixtures can be resolved into the

optically active antipodes, such as reserpine or deserpine which are laevo-rotary. The final products have valuable sedative activity and can be used as medicaments for the treatment of states of nervousness, anxiety, stress or mental disorders or can be used as intermediates in the production of such pharmacologically active compounds. The conversion of such intermediates into compounds having a sedative activity can be achieved according to known methods which are exemplified on the

- 10 laevo-rotary compounds in copending application Serial No. 526,780, filed August 5, 1955, now Patent No. 2,824,874, by E. Schlittler et al. Thus in the final products being used as intermediates free carboxylic acids can be esterified by treatment with lower diazoalkanes 15 and free hydroxy groups can be esterified, for example by treatment with acid halides, e. g. chlorides, or anhydrides, esterified hydroxyl groups can be hydrolyzed, e. g. by treatment with alkali or alkaline earth hydroxides in lower alkanols, esterified hydroxyl groups may be alcoholized, e. g. by treatment with alkali metal lower alcoholates, whereby lower carbalkoxy groups are trans-esterified. Thus, any of the compounds obtained can be converted into a compound having in 16-position a carbomethoxy group and in 18-position a trimethoxy benzoxyloxy group, which compounds show sedative activity 20 and can be used as medicaments for the treatment of states of nervousness, anxiety, stress or mental disorders.

The starting materials used in the process of the invention are known and can for example be obtained in 30 the following manner: quinone is reacted with 1,4-buta- diene-1-carboxylic acid in a Diels-Alder addition. The 6,9-dioxo-1,4,5 α ,6,9,10 α -hexahydronephthalene - 1 β - carboxylic acid of the formula:

is then reduced with sodium borohydride to 6 β -hydroxy- 9-oxo - 1,4,5 α ,6,9,10 α - hexahydronephthalene - 1 β - carboxylic acid, yielding by oxidation with perbenzoic acid 45 2,3 α -oxido-6 β -hydroxy-9 - oxo - 1,2,3,4,5 α ,6,9,10 α - octa- hydronaphthalene-1 β -carboxylic acid of the formula:

50 55 This compound, after esterification with diazomethane is subjected to a Meerwein-Ponndorf reduction with aluminum isopropoxide to yield the (1 β -9 β)-lactone of 3,6 β -oxido-9 β -hydroxy-3,4,5 α ,6,9,10 α - hexahydronephthalene-1 β -carboxylic acid of the formula:

60 65 which by addition of a lower alkanol to the double bond in 1-position is converted into a (1 β -9 β)-lactone of 2 α - lower alkoxy-3,6 β -oxido-9 β -hydroxy - 1,2,3,4,5 α ,6,9,10 α - octahydronephthalene-1 β -carboxylic acid. Addition of bromohydride to the double bond in 7-position results in the (1 β -9 β)-lactone of 2 α -lower alkoxy-3,6 β -oxido-7 α -bromo-8 β , 9 β -dihydroxy-1,2,3,4,5 α ,6,7,8,9,10 α - deca- hydronaphthalene-1 β -carboxylic acid. Oxidation with

chromic acid to the corresponding 8-oxo-compound, followed by reduction with zinc and acetic acid yields 2 α -lower alkoxy-3 β -hydroxy-8-oxo-1,2,3,4,5 α ,8,9,10 α -octahydronaphthalene-1 β -carboxylic acid of the formula:

Esterification with diazomethane, acetylation with acetic acid anhydride in pyridine, oxidation with osmium tetroxide and oxidative degradation with periodic acid gives 2 α -lower alkoxy-3 β -acetoxy-5 β -aldehydo- β -carboxy methylcyclohexane-1 β -carboxylic acid methyl ester. This after esterification with diazomethane is condensed with a tryptamine of the formula:

wherein X has the aforesaid meaning to yield a compound of the formula:

Reduction with sodium borohydride and ring closure with heating results in a compound of the formula:

The conversion of an amide thus-obtained into a compound of the formula:

can be achieved by treatment with a ring-closing agent such as phosphorous chloride.

Salts of the products obtained by the new process can be made by methods known per se and are especially acid addition salts, e. g. those of the hydrohalic acids, e. g. hydrochloric acid, nitric acid, sulfuric acid, phosphoric acids, perchloric acid, acetic, citric, oxalic, tartaric, ascorbic, methane sulfonic, hydroxyethane sulfonic, p-toluene sulfonic acid or salicylic, p-amino-salicylic acid or acetyl-salicylic acid.

The invention comprises also any process, wherein an intermediate obtainable at any stage of the process is used as starting material and the remaining steps are carried out.

The example which follows is given in the way of illustration and shall not be construed as a limitation. Many modifications will appear obvious to the man skilled in the art and it is intended that such obvious modifications are also comprised by my invention. Temperatures are given in degrees centigrade.

Example

250 mg. of O-acetyl methyl didehydro-reserpate chloride is dissolved in 20 ml. of 50 percent aqueous ethanol and made alkaline by the addition of 5 ml. of 0.5 N potassium hydroxide. The solution is shaken for two and one-half hours in an atmosphere of hydrogen at 20 pounds' pressure in the presence of 100 mg. of 10 percent palladium on charcoal. After removal of the catalyst the solution is diluted with 100 ml. of methylene chloride and washed twice with 50 ml. of water. The methylene chloride solution is dried over sodium sulfate and the solvent evaporated under reduced pressure. Chromatography over activated alumina yields the pure dl-O-acetyl methyl reserpate.

What is claimed is:

1. Process for the manufacture of a member of the group consisting of compounds of the formula

in which R represents a member of the group consisting of hydrogen and methyl, R' represents lower alkyl, and R''' stands for a member of the group consisting of hydrogen and methoxy, and salts thereof, which comprises treating a member of the group consisting of compounds of the formula

in which R, R' and R''' have the above-given meaning, R'' stands for a member of the group consisting of hydrogen, the acyl radical of lower fatty acids, monocyclic aromatic carboxylic acids, monocyclic aryl-lower alkoxy acids, monocyclic heterocyclic carboxylic acids and monocyclic aryl sulfonic acids, and A represents an anion, and salts thereof, with hydrogen in the presence of a catalyst containing at least one element selected from the

eighth group of the periodic system and in the presence of an alkaline reagent.

2. Process according to claim 1, wherein A stands for a halogen anion.

3. Process according to claim 2, wherein A stands for 5 a chlorine anion.

4. Process according to claim 1, wherein treatment with hydrogen is carried out in the presence of an alkali metal hydroxide.

5. Process according to claim 4, wherein treatment 10

with hydrogen is carried out in the presence of potassium hydroxide.

6. Process according to claim 1, wherein treatment with hydrogen is carried out in the presence of a catalyst containing palladium.
